UNITED STATES PATENT OFFICE

GEORGE H. PERRINE, DECEASED, LATE OF HASTINGS-UPON-HUDSON, NEW YORK, BY
ANNIE E. PERRINE, EXECUTRIX, OF HASTINGS-UPON-HUDSON, NEW YORK, AS-
SIGNOR TO SCOVILL MANUFACTURING COMPANY, OF WATERBURY, CONNECTICUT, A
CORPORATION OF CONNECTICUT

SELF LOCKING SLIDE LOOP

Application filed December 29, 1930. Serial No. 505,412.

The object of this invention is to provide a metallic loop which when applied to an article, such as a suspender end or strap like those used, for example, on overalls, may be 5 adjusted on such suspender or strap to properly connect with another object, such as a button or loop on the waistband of a garment, to obtain the proper elevation of the garment, or its fit on the wearer, the loop being locked 10 by its own mechanism in given working position.

In furtherance of this object, the invention consists of a loop, preferably made of wire 15 bent to shape and having at its upper end a cross bar and below it inturned limbs to which cross bar is pivoted a swinging bar, in such manner that when the suspender or strap has one end passed beneath the upper cross bar and then over the swinging bar and then be- 20neath such swinging bar and bent back again below the cross bar of the loop and over the inturned limbs, the tension on the suspender or strap in use will serve to draw the swinging bar into gripping action on the suspender or 25 strap and the inturned limbs acting as an abutment and be held in any given or adjusted position thereon. By the arrangement de- 30scribed, the end of the suspender or strap is not returned upwardly against the back of the suspender or strap, but is left to hang down freely back of the device, thereby in a measure 35 protecting the undergarments against direct contact with the device.

In order to increase the tractive effect of 35 the swinging bar on the suspender or strap, it is preferably made of angular cross section.

The invention will now more fully be explained and finally claimed.

In the accompanying drawing illustrating 40 the invention, in the several figures of which like parts are similarly designated, Figure 1 is a front elevation, and Fig. 2 is a side elevation showing the self-locking slide loop in position on the suspender or strap. Fig. 3 45 is a perspective view of the self-locking slide loop detached. Fig. 4 is a perspective view of a modification in which the loop is constructed to be engaged not with a button, but with a loop or tab extending from the garment to be suspended.

The invention is shown as applied to a well known form of button loop made of wire, such as shown in the Howe patent, No. 961,718, granted June 14, 1910, but the invention is susceptible of use on other forms of loops.

In the device shown in Figs. 1, 2 and 3, the loop has an upper cross bar 1, the ends of which are reversely curved to form the approaching limbs 2 substantially parallel with bar 1, and these lower limbs 2 are then bent downwardly to form the spring or yielding limbs 3, the ends of which are made with eyes 4, in which is pivotally suspended a button-engaging loop 5. Such a device is useful, 55 among other things, for application to the ends of suspenders of overalls to engage buttons on the waistband or waist portion of the garment.

In order to permit adjustment of the device to suit the wearer, there is pivotally mounted at the front of the loop on the upper cross bar 1, a swinging bar 6, the ends of which are formed as eyes 7, which engage the cross bar 1 in such manner that the swinging bar gravitates downwardly so as normally to overlie the lower limbs 2. The lower limbs 2 thus serve as an abutment for the swinging bar. This swinging bar preferably is made of wire of angular cross section in order to obtain the advantage of increased tractive effect on the suspender strap to hold the device in adjusted position; although the invention is not limited to the use of a swinging bar made of material angular in cross section.

As shown in Figs. 1 and 2, the device is applied to a suspender or strap by passing the end of the suspender or strap 8 from the rear underneath the cross bar 1 and over the 90 swinging bar 6 and then beneath the swinging bar and out again backwardly through the device and beneath its cross bar 1 and over its lower limbs 2, so that the free end 8' of the suspender or strap may hang down back of the device in unconfined position. In this position, the suspender or strap end 8' may serve as a guard for the device to prevent its direct contact with the apparel of the wearer or user.

A self locking slide loop thus constructed is capable of being adjusted at pleasure and is self locking in the position to which adjusted.

5. In Fig. 4, the construction just above described is repeated and like parts are similarly designated, excepting that instead of having eyes like the eyes 4 in the construction shown in Figs. 1 to 3, the ends of the 10 limbs 3 are crossed at 9 and then reversely bent as at 10, preferably crossing one another, and these ends thus serve to engage a loop or tab 11 attached to a garment, in the place of buttons. Engagement with and dis- 15 engagement from the tab 11 is effected by pressing upon the limbs 3 in the direction of the arrows 12 and 13 which causes the ends 10 to move away from one another so as to engage with or be disengaged from the tab 11.
20. Variations are permissible within the principle of the invention and the scope of the claims following.

What is claimed is:—

1. A self-locking slide loop, comprising a 25 loop having an upper cross bar and reversely curved approaching limbs substantially parallel with the upper cross bar and a garment-engaging element arranged at the bottom of the device, and a swinging bar piv- 30 oted to the upper cross bar and hanging downwardly therefrom and overlying the reversely curved approaching limbs.
2. A self-locking slide loop, comprising a 35 loop having an upper cross bar and reversely curved approaching limbs substantially parallel with the upper cross bar and a garment- 40 engaging element arranged at the bottom of the device, and a swinging bar of angular cross section, pivoted to the upper cross bar at the front of the loop and hanging downwardly from said cross bar, combined with

a suspender or strap engaging the loop by passing said suspender or strap forwardly beneath the upper cross bar and then over the upper portion of the swinging bar and the lower cross limbs and then below said swinging bar and backwardly beneath the upper bar and over the lower cross limbs to the back of the loop. 70

3. A self-locking slide loop, comprising a 75 loop having an upper cross bar and reverse- 80 ly curved approaching limbs substantially parallel with the upper cross bar and a garment-engaging element arranged at the bottom of the device, and a swinging bar piv- 85 oted to the upper cross bar and hanging downwardly therefrom, combined with a sus- 90 pender or strap engaging the loop by pass- 95 ing said suspender or strap forwardly beneath the upper cross bar and then over the upper portion of the swinging bar and then below said swinging bar and backwardly over the approaching limbs, the last-men- 100 tioned portion of the suspender or strap hanging downwardly at the back of the loop and guarding said loop against direct contact with the wearer.

4. A self-locking slide loop, comprising a 105 loop having an upper cross bar and garment- 110 engaging elements depending therefrom, and a swinging bar pivoted to the upper cross bar and hanging downwardly therefrom, the garment-engaging elements comprising crossed side limbs having returned ends adapted to be moved apart by sidewise pressure to engage with and be disengaged from a part on a garment.

In testimony whereof I have hereunto set my hand this 23rd day of September, 1930.

ANNIE E. PERRINE, 105
Executrix of George H. Perrine, Deceased.
